UNITED STATES PATENT OFFICE.

EDGAR F. HATHAWAY, OF WELLESLEY, MASSACHUSETTS, ASSIGNOR TO SHAWMUT ENGINEERING COMPANY, OF BOSTON, MASSACHUSETTS, A CORPORATION OF MASSACHUSETTS.

TUFT FRAME FOR WEAVING PILE FABRICS.

Application filed January 29, 1923. Serial No. 615,578.

To all whom it may concern:

Be it known that I, EDGAR F. HATHAWAY, a citizen of the United States, and resident of Wellesley, in the county of Norfolk and 5 State of Massachusetts, have invented certain new and useful Improvements in Tuft Frames for Weaving Pile Fabrics, of which the following is a specification.

This invention relates to looms of the 10 type used in weaving Axminster carpets or similar pile fabrics, and is intended to minimize waste of material and economize labor by requiring less frequent renewal of the tuft yarn on the yarn spool. 15 According to the practice heretofore prevailing, the tuft yarn which forms the material for the pile-forming tufts was temporarily clamped to the barrel of the spool by a longitudinal wire or rod, then wrapped or 20 wound around the spool until only enough of the outer ends of the yarn remained to be inserted through the tuft tubes, the clamping wires then being withdrawn endwise. When in use the yarn was unwound intermittently from the spool as required to provide 25 tufts for insertion into the fabric being woven until there remained only one and a half or perhaps two complete turns of the yarn around the spool barrel which were required to hold the yarn in place. At this 30 point the spool had to be removed to renew the yarn since there was no longer enough yarn remaining to keep in position on the spool and furnish further tufts for the fabric. 35 These last anchoring turns of the yarn, as well as the stretches of yarn extending from the line where the yarn clears the spool to the delivery ends of the tuft guides or tubes, sufficient in length to furnish tufts for a substantial number of additional rugs, 40 if utilized, were lost or wasted.

It is the object of the present invention to minimize this waste and to render a given length of yarn available for a greater number of rugs, at the same time rendering unnecessary such frequent renewal of the yarn, and to this end the invention comprises, broadly speaking, the provision of means forming an attaching or retaining connection between the yarn spool and the tuft yarn that allows the inner end portions of the yarn to fully unwind from the spool and preferably to remain available for use until

the inner yarn ends reach or approach the tuft tubes through which they are guided or 55 fed to the fabric.

This and other features of the invention will be explained in the following specification and will be defined in the claims hereto annexed.

In the accompanying drawings I have illustrated several forms embodying the principles of this invention, in which:

Figure 1 is a front elevation of a detached tuft frame showing the inner ends of the yarn 65 elements suspended adjacent to the tuft guides or tubes after they have completely unwound from the spool.

Figure 2 is a transverse section illustrating the same arrangement.

Figure 3 is a similar view showing the unwinding in the reverse direction to that illustrated in Figure 2.

Figure 4 is an end elevation illustrating a modified arrangement of the yarn-holding 75 means.

Figure 5 is a detailed front elevation on an enlarged scale showing the yarn-engaging means illustrated in Figure 4.

Figure 6 is a transverse section of a modified form of yarn spool and attaching means.

Figure 7 is a similar view on a larger scale showing another modification to that shown in Figure 6.

In the practice of this invention, according to the forms illustrated in Figures 1, 2 and 3, the spool barrel 1, is provided with the usual heads or flanges 2, and journals 3 which are rotatably supported in bearings in the brackets 4^a, which are secured to and project from the longitudinal carrier bar 4, on one side of which are secured, in any suitable manner, the guides or, in this case, tuft tubes 5, through which the outer ends 85 of the yarn on the spool are threaded and by which the yarn elements are spaced and guided to present short lengths or tufts intermittently to the fabric to be woven.

Along one side of the spool barrel 1 is 100 formed a groove or recess, as shown at 1^a, for the purpose of receiving and loosely retaining the yarn-holding portion of the attachment or device that forms an expandible connection between the inner ends of the 105 yarn and the spool.

This expandible connection may be of any suitable form but, as shown, it comprises a flexible apron 6, whose anchored edge is secured to the spool in any suitable manner, as 5 by means of a longitudinal row of tacks 7. At its free end the apron or connecting member 6 is provided with a yarn-retaining or engaging device which, as illustrated in Figures 1 to 3, comprises a longitudinal 10 trough-like member 8 forming the female element of a clamping couple, the inner ends of the yarn *t* being clamped thereto by means of an inserted clamping rod 9 which pinches the yarn ends into the shallow 15 trough of the member 8.

As similar patterns of yarn on the spool may be unwound in relatively reverse directions, provision is made so that if need be the yarn may unwind properly from the 20 spool when the spool is rotating in one direction or the reverse. Provision is, therefore, made for locating the anchorage of the connecting member to the spool in such a position that the yarn-retaining portion 8, 25 when wound from its anchorage in either direction, will lie inside the recess 1^a. This may be accomplished by locating the fastening tacks 7, or other fastening means, so that the line where the apron 6 is free to move 30 out from the spool periphery is approximately opposite the medial line of the bottom of the recess so that the yarn-retaining device will properly lie in said recess with its apron in contact with the spool periphery. 35 whether carried around the spool barrel in one direction or the other, the length of apron being determined to allow the yarn-clamping element to lie within said recess. For a similar reason the yarn-engaging element 40 of the expandible connection is made double and reversible. As shown in cross section in Figures 2 and 3, the yarn-engaging element 8 is practically S shaped so as to present an open or clamping side outward. 45 whether the apron be wound around the spool in one direction or reversely. Wound in the direction shown in Figure 2, the open side of the yarn-holding element 8 is that next to the apron, while wound in the direction indicated in full line in Figure 3 the 50 yarn-engaging element would have its free end exposed outwardly to receive the cooperating clamping rod or member 9.

In the arrangement shown in Figure 6 the 55 spool barrel 1, opposite the recess 1^a, has an opposite longitudinal recess or groove 1^b, adapted to receive a number of clamping or wedging pieces 10 between which the anchored end of the apron is pinched, said 60 longitudinal strips 10 being frictionally held in the groove 1^b.

In Figure 7 another modified form of connection with the spool is shown. In this case a hollow spool 10, which may be of 65 metal, is formed with interior hollow rib

10^a, and the apron 6 is fastened between two longitudinally extending spring bow arms 11 by rivets or the like and are sprung through the narrow entrance to the hollow rib so as to permit their expanding into 70 frictional engagement with the interior of said rib to hold the apron or attaching member detachably anchored to the spool, this same construction being that shown in Figure 4, the spool 10 having also an opposite 75 recess 10^b for receiving the yarn-retaining element.

In the case of the form shown in Figures 4 and 5, the yarn-engaging element comprises a helically coiled wire spring 12, attached at intervals by loops 12^a, or other connections with the lower end of the apron 6. In this case in setting up the spool the 80 yarn ends are carried between adjacent coils or turns of the helical wire 12 by which they are pinched by the contractile force of the spring so as to hold them with sufficient grip for the purpose of suspending the yarn ends therefrom.

Whatever detail of construction may be 85 employed in carrying out the principles of the invention it will be seen that provision is made for an expandible connection between the inner ends of the yarn elements from which the tufts are formed and the 90 yarn-carrying spool so that the yarn is permitted to completely unwind from the spool and even travel until its rear ends reach the intake ends of the tuft guides 5 before the 95 yarn ends become unavailable for supplying 100 further tufts to the fabric.

As this saving of the inner ends of the 105 yarn is equal, ordinarily, to more than twice the circumference of the spool barrel there is utilized enough additional yarn with each 110 setting up of the tube frame to provide tufts for a substantial number of additional rugs, and it will also be seen that by reason of this additional utilization of the yarn, renewal of the spools at less frequent intervals is required, all of which effects a very 115 substantial saving in material and in labor.

What I claim is:

1. In a tube frame for weaving tufted 115 fabrics, the combination of a rotatable yarn spool, a cooperating series of tuft guiding members, and means forming a connecting extension between the inner yarn-ends and the spool whereby said yarn-ends are permitted to unwind from the spool and still 120 remain attached thereto, substantially as described.

2. In a tube frame for weaving tufted 125 fabrics, the combination with a yarn supporting spool, a cooperative series of tuft-spacing members arranged in juxtaposition thereto so as to receive the yarn, and means for attaching the inner ends of the yarn to the spool, said means forming an effective connection between the inner ends of the 130

yarn and the spool after the yarn ends have left the spool and approach the tuft spacing members, substantially as described.

3. In a tube frame for weaving tufted fabrics, the combination of a rotatable yarn-carrying spool a cooperating series of yarn-guiding tuft tubes, a yarn-attaching member adapted to wind on and unwind from the spool and thus form an extension of the 10 yarn ends to maintain connection between the yarn ends and the spool after the yarn-ends have unwound from the spool, substantially as described.

4. In a tuft frame for weaving pile fabrics, the combination of a yarn-carrying spool and a flexible yarn-attaching member adapted to partly surround the spool to which one end is attached and provided with 15 yarn-retaining means at its other end there- 20 by affording an extensible connection between the yarn and the yarn spool and permitting the yarn to unwind without losing connection with the spool, substantially as described.

25 5. A yarn saving device for a yarn-carrying spool, embracing in its construction a flexible apron adapted to be attached to the yarn spool along one of its edges and having at its opposite edge means for gripping 30 the inner ends of the yarn elements thereby affording an extensible connection between the spool and the yarn elements, substantially as described.

35 6. A yarn saving device for a yarn-engaging spool, embracing a connecting member adapted to lie lengthwise on the spool and be attached thereto, and a yarn-retaining device for holding the inner ends of the 40 yarn in operative connection with the spool, substantially as described.

7. The combination with a yarn spool having a longitudinal recess in its periph-

ery, of a yarn-attaching means provided at one longitudinal edge with means for anchoring it to the spool and having at its 45 free edge a yarn-holding device by which the yarn ends are extensibly connected with the spool substantially as described.

8. The combination with a tuft yarn spool, of means for detachably and exten- 50 sibly attaching the inner yarn ends to the spool thereby permitting the yarn ends to unwind from the spool and still retain operative connection therewith, substantially as described.

55 9. The combination with a tuft yarn spool provided with a longitudinal recess in its periphery, a yarn-holding device flexibly connected with the spool and arranged to permit the yarn to be wound or unwound 60 in either direction outside of the holding device seated in said recess, substantially as described.

10. A tuft yarn spool provided on opposite sides of its axis with longitudinal recesses, and a yarn-attaching device detachably anchored in one recess and having a 65 yarn-holding member adapted to lie in the other recess when the yarn is wound on the spool and to swing out of said recess when 70 the yarn is unwound, substantially as described.

11. The combination with a tuft yarn spool and yarn-attaching means anchored thereto at one edge and having a holding 75 device for receiving and detachably holding the inner ends of the yarn, said holding device being formed to hold the yarn properly for winding in either direction, substan- 80 tially as described.

In witness whereof, I have subscribed the above specification.

EDGAR F. HATHAWAY
